UNITED STATES PATENT OFFICE.

PERCY ROY BLACKMORE, OF ILFORD, ENGLAND.

MOUNT FOR PRINTERS' AND LIKE BLOCKS.

1,164,329.

Specification of Letters Patent. Patented Dec. 14, 1915.

Application filed October 6, 1913. Serial No. 793,577.

To all whom it may concern:

Be it known that I, PERCY ROY BLACKMORE, subject of the King of Great Britain and Ireland, residing at 126 Empress avenue, Ilford, in the county of Essex, England, compositor, have invented new and useful Improvements in Mounts for Printers' and like Blocks, of which the following is a specification.

10 My invention relates to improvements in mounts or mounting boards for process line and like blocks, stereos or the like of the type comprising compound wood and metal blocks.

15 The objects of my invention are to provide a simple and rigid backing for the printing or like surfaces which will not warp or buckle which shall be more durable than the present wooden backing now used

20 and in which the marginal flange or beard now necessary to pin the printing surface to its backing, may be eliminated when required.

25 Suitable arrangements may be made to secure the inclosing material to the insertion and pins or nails having suitable heads are secured on the various surfaces of the insertion so that their heads project the required distance and act as chaplets to support and 30 position the insertion in the casting box, so that when the stereo or other metal or alloy is poured therein, the insertion will be totally inclosed by a reinforcing case, which also acts to insulate it from the action of atmospheric and like changes.

35 The printing surface may be attached to the prepared mount in the usual manner or when it is desired to eliminate the marginal flange or beard it may be attached by 40 casting or sweating one of the stereo or other metal plates or layers, thereto, either prior to or during the preparation of the mount. After the printing surface is attached the whole block is trimmed to gage 45 in the usual manner.

In order that my invention may be more readily understood reference is had to the accompanying drawings in which:—

Figures 1 and 2 are two vertical sections at 50 right angles of a block in which the insertion is totally incased by the stereo or other metal or alloy, and Fig. 3 is a section showing a method of casting the stereo or other metal or alloy around the insertion.

55 Referring now to the drawings a prepared

piece of block of insertion D¹ of a size slightly less than that of the printing surface to be mounted has a complete shell or casing around it so as to be totally surrounded or covered thereby. The block of insertion D¹ has suitable holes, channels, ducts, apertures, recesses or the like *d* cut or otherwise formed therein to allow the stereo or other metal or alloy to engage them and thereby key the case H to the insertion D¹. 60 The printing surface A may either be secured to the case H in the process of casting the latter around the insertion D¹, in which case the marginal flange or beard may be eliminated, or it may be secured by nails, 65 pins, tacks or the like passed through a marginal flange or beard into the mount in the usual way.

The method of casting the casing H around the insertion D¹ is shown in Fig. 3 in 75 which the printing surface A is tinned or fluxed on its back and laid face downward in a casting box.

Pins, nails or the like J having suitable heads *j* are secured at intervals over the 80 block of insertion D¹ so that the heads project above the surface thereof to an extent about equal to the thickness of the casing H required. Type high gages K are brought against the side pins J and the cover L of 85 the casting box closed down so as to press upon the top ones so as to hold the block in position while the stereo or other metal is poured.

What I claim as my invention and desire 90 to secure by Letters Patent is:—

In a mount for printers' blocks a single piece of insertion one side of which is not greatly less in area than the mount, pins having projecting heads distributed over the 95 larger surfaces of the piece of insertion, through holes in the insertion, an enveloping case of metal cast around and completely enveloping said insertion on all its faces and connecting strips of metal between 100 the larger surfaces of the enveloping casting through the holes in the insertion to prevent bulging of the top and bottom faces of the enveloping case.

In witness whereof I have hereunto set 105 my hand in the presence of two witnesses.

PERCY ROY BLACKMORE.
